UNITED STATES PATENT OFFICE.

WILLIAM J. BRISCOE, OF HAVERHILL, MASSACHUSETTS.

HOLDER FOR TOILET-PAPER AND PAPER TOWELS.

1,198,102.

Specification of Letters Patent. Patented Sept. 12, 1916.

Application filed February 16, 1916. Serial No. 78,731.

To all whom it may concern:

Be it known that I, WILLIAM J. BRISCOE, a subject of the King of England, residing at Haverhill, in the county of Essex and State of Massachusetts, have invented certain new and useful Improvements in Holders for Toilet-Paper and Paper Towels, of which the following is a specification, reference being had to the accompanying drawings.

This invention relates to holders for toilet paper and particularly to holders for rolls of paper of that class in which the roll holder can only rotate a single limited extent and when released returns to its initial position, thus limiting the amount of paper which can be drawn off by any single actuation.

The general object of my invention is the provision of a device of this character, particularly designed to hold the larger and cheaper rolls of paper, yet which shall operate in the manner above described.

A further object is to provide a roll holder of a very simple construction which may be very cheaply made and which may be readily assembled and disassembled.

Still another object is to so construct the brackets supporting the core on which the paper is wound that the brackets may be readily separated from each other to permit the withdrawal of the core, the brackets being held in their engaged position by means of a spring.

Other objects will appear in the course of the following description.

My invention is illustrated in the accompanying drawings, wherein:

Figure 1 is a longitudinal sectional view of a roll holder constructed in accordance with my invention, the core being partly in section and the section of the core being taken on the line 1-1 of Fig. 3; Fig. 2 is an end view looking toward the bracket 16; Fig. 3 is a section on the line 3-3 of Fig. 1; Fig. 4 is an end elevation of the core looking toward the hub 25; Fig. 5 is a fragmentary elevation of the inside face of the bracket 11.

Referring to these drawings, 10 designates the base of the bracket which is perforated or otherwise formed so that it may be attached to a wall or to any other suitable supporting member, this base having at one end the integral outwardly extending bracket 11 which adjacent its extremity, is formed with the circular aperture 12 and

which inward of this aperture is formed with the longitudinally extending lug 13. The opposite end of the base 10 is formed with a medially disposed knuckle 14, longitudinally perforated, and inward of this knuckle the base is thickened, as at 15, to form a stop for the bracket 16 which is pivoted to the knuckle 14. This bracket 16 at its base is formed with the oppositely disposed spaced knuckles 17 which are longitudinally perforated, and passing through the knuckles 17 and 14 is the pintle 18. It will be seen that when the bracket is at right angles to the base 10 it will contact with the stop 15, but that the bracket may be turned outward to any desired degree.

In order to hold the bracket in a position at right angles to the base 10, I provide the spring 19, this spring being approximately 75 U-shaped in form and having its legs coiled a plurality of times around the pintle 18, the knuckle 14 being of less length than the space between the knuckles 17 so as to accommodate the coils of wire. The extremities of the spring are then turned angularly beneath the base 10 and disposed in grooves 20 in the base, as illustrated most clearly in Fig. 1. The extremity of the bracket 16 is formed with a many-sided aperture 21 85 illustrated as oblong in form.

The core upon which the roll is supported comprises a triangular body 22, preferably of cast metal and preferably hollow, the bore 23 extending longitudinally through the core. At one end this core 22 is formed with the outwardly projecting annular externally screw threaded hub 24 while at its other end there is formed the solid hub 25 with an integral trunnion 26 which is cylindrical in cross section and is adapted to be disposed in the perforation 12. This solid hub 25 has a radial extension 27 forming a stop coacting with the lug 13 on the bracket 11. The face of the core is provided with screw 95 threaded perforations 28 and 29.

Disposed within the core is a rod or shaft 30 which at its outer end is rectangular in cross section, as at 31, and is designed to fit within the rectangular aperture 21. At the neck or junction between the round portion of the shaft 30 and the rectangular portion thereof is formed the circular shoulder 32, while rotatably mounted upon the extremity of the round portion of the shaft is a collar 33 and encircling the shaft is a coiled spring 34, one end of which is engaged with the

fixed shoulder or collar 32 while the other end is engaged with the relatively rotatable shoulder or collar 33. To this end each of these collars or shoulders is formed with 5 parallel apertures 35 through which the wire forming the spring is passed and then rebent upon itself, thus holding the spring in firm engagement with the shoulders or collars. The collar or shoulder 33 is also 10 formed with a recess 36 in its periphery which is adapted to be engaged by a screw 37 passed through the perforation 29 to thus hold the collar 33 from rotation. Through the perforation 28 passes a limiting screw 15 38 which bears not against the periphery of the collar 32 but against the inside face thereof to limit the inward movement of the collar but permit the collar to rotate. Engaging the screw threaded exterior of 20 the hub 24 is an interiorly screw threaded cap 39 having a central circular aperture 40 through which the rectangular shank 31 of the shaft 30 projects. In order to assemble 25 these parts, the shaft 30 with the spring 34 and allied elements is disposed within the bore of the core and then the screw 37 is engaged with the socket or recess 36. The screw 38 is then screwed inward and thus the shaft is held securely in place. The 30 cap 39 may then be disposed upon the hub 24. The roll of paper is then placed upon the core 22, the core 22 being slightly tapering for this purpose, and then the circular trunnion 26 is inserted in the circular perforation 12 while the rectangular trunnion formed by the shank 31 is disposed within the rectangular opening 21 of the bracket 16, the spring 19 holding this bracket 16 in a 35 position perpendicular to the base 10. When 40 the paper has been exhausted and it is desired to remove the core, it is only necessary to shift the bracket 16 away from the bracket 11 against the action of the spring 19 whereupon the core may be readily withdrawn. In rolling paper to be placed upon 45 this core it should be rolled over a triangular mandrel which of course must be tapering in order to provide for the insertion of the core 22 but otherwise than this the paper 50 may be rolled in exactly the same manner in which rolls of toilet paper are ordinarily rolled up upon a circular base. Furthermore, this triangular core is adapted to be used with ordinary paper rolls which are 55 wound upon a circular mandrel. When a roll of this kind is forced upon the triangular core, the inner layers of the roll tend to take a somewhat triangular form which binds the roll upon the core and prevents 60 the roll rotating upon the core.

It will be obvious now that when it is desired to withdraw paper from the roll, the core will rotate through nearly an entire revolution and that then the stop 23 will 65 come in contact with the stop 13 preventing

any further rotation of the core and the paper must be torn off. As soon as the paper is torn off, the spring 34 will act to return the roll to its original position thus necessitating that relatively short lengths of 70 paper be torn off from the roll and thus preventing waste of the paper. While this has been accomplished in holders wherein the paper is wound upon a relatively flat plate so that the roll has an elliptical form, it has 75 not been possible heretofore to provide this mechanism for the large circular rolls in which form relatively cheap paper ordinarily comes, and, as stated before, one of the 80 objects of my invention is to provide a construction of this character which may be used with rolls of cheap paper.

My invention is simple, may be very cheaply constructed, and is entirely effective 85 for the purpose intended.

Having described my invention, what I claim is:

1. A holder for toilet paper comprising a core having at one end an annular hub and at the other a solid hub formed with a central circular trunnion and a radially disposed stop, the bracket at that end being formed with a circular perforation and a stop disposed in the path of movement of the first-named stop, a shaft loosely disposed within the core, a spiral spring surrounding the shaft, one end of the spiral spring being operatively engaged with the shaft, a collar loosely surrounding the shaft at the other end and with which the spiral spring is engaged, means for engaging the collar with the core, said shaft at the end opposite the roller being rectangular in section and the adjacent bracket being formed with a rectangular aperture to receive the rectangular end of said shaft. 95

2. A roll holder for toilet paper comprising a base having at one end an outwardly extending rigid bracket formed with a circular perforation and with an inwardly extending lug forming a stop, a bracket hinged to the other end of the base, a spring yieldingly holding the bracket in parallel relation to the first-named bracket, said second named bracket being formed at its extremity with a rectangular opening and a core disposed between the brackets and engaging therewith, said core being many-sided in cross section and hollow, one end of the core having an integral hub with a radiating lug and a central trunnion adapted to be engaged in the circular perforation of the first-named bracket, the other end of the core having an angular exteriorly screw-threaded hub, a cap having a central perforation having screw-threaded engagement with the screw-threaded hub, a shaft disposed within the core, the shaft at its outer end having a many-sided shank and an integral collar, a loose collar surrounding the 100 105 110 115 120 125 130

other end of the shaft, a coiled spring surrounding the shaft and engaged with said collar, the many-sided shank being adapted to engage the rectangular opening in the bracket, and a screw passing through the core and engaging the loose collar to the core.

In testimony whereof I hereunto affix my signature in the presence of three witnesses.

WILLIAM J. BRISCOE.
